UNITED STATES PATENT OFFICE

2,568,282

TRUSS

John Gutsch, Chicago, Ill.

Application August 16, 1948, Serial No. 44,451

5 Claims. (Cl. 128—108)

1

The present invention relates to rupture or hernia trusses, and has for its main object the provision of a pad made in the form of a metallic shell, perforated at its body-contacting surface permitting respiration of the skin and the drainage of the perspiration.

Another object of the present invention is the provision of a truss pad of the character indicated, made in a form of a metallic shell, composed of a pair of complementary sections, which may easily be formed by and upon a suitable stamping machine, and which sections may readily be joined together by welding or other suitable means.

A still further object of the present invention is the provision of means associated with the pad and co-acting with the truss supporting bar, whereby the pad may be angularly adjusted with relation to the truss supporting bar, so as to properly adjust the pad to the area of the wearer's body with which the pad is to contact.

Another object of the present invention is to generally improve a truss pad of the character above indicated.

With the above general objects in view and others that will appear as the invention is better understood, the same consists in the novel construction, combination and arrangement of parts hereinafter more fully described, illustrated in the accompanying drawing and pointed out in the appended claims.

In the drawing forming a part of this application and in which like designating characters refer to corresponding parts throughout the several views:

Fig. 1 is a side elevational view of the truss with a pair of pads, viewing the truss from the side away from the wearer's body;

Fig. 2 is the side elevational view of a pair of shells prior to their joining for effecting the pad;

Fig. 3 is a view similar to that of Fig. 1, with a single pad supported upon the end of a truss supporting bar;

Fig. 4 is an enlarged cross-sectional view through the pad, taken on line 4—4 of Fig. 1; and

Fig. 5 is an enlarged cross-sectional view, on line 5—5 of Fig. 1.

Referring in detail to the present drawing there is shown in Fig. 1 a truss supporting bar 10, for supporting thereon a pair of pads, generally indicated by 11. In Fig. 3 there is shown a similar supporting bar 12 for supporting a single pad 11. Both of said bars are made of oblong, comparatively thin and narrow strips of resilient metallic material, so formed as to bear against the pads in order to maintain them in a proper

2

contacual relation with the wearer's body. The ends of said bar 10 or 12 are connected by a clasp or other device 13 to a belt 14 which encompasses the body of the wearer.

5 Each of said bars 10 and 12 defines a substantially horizontal portion 15, and an upwardly turned portion 16, the two effecting a corner 17, adjacent which the pad 11 is supported upon said horizontal portion 15 of bar 10 or 12.

10 Centrally of bar 10 at the horizontal portion 15 thereof is an oblong slot 18, adjacent corner 17. Coextensively with said corner 17, in bar 10 slot 19 is made, said latter slot 19 extends into the lower end of the upwardly turned portion 16 of bar 10. In bar 12 one slot 20 is made therein, which extends into the horizontal and the upwardly turned portions thereof.

15 Referring now to the construction of pad 11, the same is substantially oval or pear-shaped, and is composed of a pair of complementary sections, one a body-contacting section 21, and the other the outer section 22. The former is provided upon its contacting face with a plurality of apertures 23, which permit the respiration of 20 the skin, with which the section contacts, and drainage therethrough of the perspiration. The outer face of said section 21 is highly polished 25 and is convex.

20 The outer section 22 is provided with a central oblong opening 24, through which access may be had into the inside of the shell defined by said sections 21 and 22. Made upon the outer face of the said outer section 22 is a pair of longitudinal slots 25, each disposed between the margin defined by said opening 24 and the adjacent edge 30 of the pad. These slots 25 are positioned adjacent the upper or wider end of the pad.

25 Two sections 21 and 22 along their edges are connected by welding, as at 26, or by any other suitable means. Thereby said sections 21 and 22 35 will define a hollow shell.

When the pad 11 is brought into an operative relation with bar 10 or 12, with the outer face of section 22 in contact therewith, and substantially in a transverse relation with one or the other of said bars, slots 18, 19 and 20 will be in a substantially transverse relation with slots 25 40 in said section 22. Through the crossing points of the two sets of slots screws 27 are extended, with the heads thereof engaging the outer faces 45 of said bars 10 and 12, as the case may be. The inner threaded ends of said screws 27 extend into the shell defined by sections 21 and 22, and are there engaged by nuts 28. Person's finger 50 extended through the opening 24 holds nut 28 against rotation, while a screw-driver applied 55 to the screw head turns screw 27 for tightening

the said screw and nut 28, and thereby clamping the pad 11 and the bar 10 or 12 together, for maintaining pad 11 in a rigid adjusted relation with the bar.

As is obvious slots 18, 19 and 20 permit the pad 11 to be longitudinally adjusted with relation to the bars 10 and 12, respectively, while slots 25 permit the pad 11 to be adjusted in a transverse relation with said bars. The respective slots also permit the angular adjustment. If for instance one screw 27 in one pad 11 is tightened, with the other screw loose, the latter screw will permit the angular shifting of the pad, the first screw acting as a pivot. Upon a proper angular adjustment of the pad the second screw is of course also tightened in order to maintain the pad 11 in a rigid adjusted relation with the bar 10 or 12. When one of said screws 27 enters the upper termination of slot 19 or 20, which is extended into the upwardly turned portion 16 of bar 10 or 12, as the case may be, then it is possible to adjust the pad 11 almost in a horizontal relative position with respect to the one or the other of the said bars.

It is noted that the shape of a pear fits the pad for inguinal canal, and permits the wearer to assume a sitting position without forcing the pad out of place with the area of rupture. The pad being made as a hollow casing is of course comparatively light and easy to wear. The convex shape of the body-contacting wall of section 21 exerts sufficient pressure upon the ruptured area, but does not cause further rupture as often occurs with pads having sharp or deep bulges.

It is further observed that each of the said sections 21 and 22 may be moulded by the same die. When so moulded the walls that are oppositely disposed in the final formation of the pad would each become convex. This would not constitute a serious objection, because before the sections are joined along line 26, the wall in section 22 may be either hammered down or otherwise flattened out to bring it to a straight even plane, as seen in Fig. 4.

From the hereinabove description it will be readily seen that the pad herein described is sanitary in a high degree. Since the same is made in the form of a hollow casing which is impervious to water, it may be periodically cleaned by washing. The pad being built out of a pair of complementary sections joined together, lends itself to easy manufacture, without requiring costly machinery or great many operations.

While there are described herein preferred embodiments of the present invention, it is nevertheless to be understood that minor changes may be made therein without departing from the spirit and scope of the invention as claimed.

What I claim as new is:

1. As an article of manufacture, a truss pad comprising a hollow casing made of a rigid sheet of material and composed of a pair of complementary sections joined at their edges, said sections defining a pair of oppositely disposed, substantially parallel walls, the exterior of the wall in one of said sections constituting a body-contacting surface, the opposite wall in the other of said sections being provided with an opening affording access into said casing, said opening being of appreciable width sufficient to admit a finger therethrough and extending throughout the major portion of the height of the casing, and said latter wall being further provided with a pair of parallel slots on opposite sides of said

opening, each disposed between said opening and the margin of said casing.

2. A truss comprising a pad including a hollow casing having a pair of complementary sections joined together at the edges thereof, one of said sections forming a wall having a pair of vertical laterally spaced slots therein, a supporting bar for the pad having a portion slotted horizontally to coact with one of the slots in the pad and having another portion of the bar slotted angularly with respect to the other of the slots in the pad, and fastenings extending respectively through said slotted portions and slots and adjustable with respect to each for adjustably securing the pad to the bar.

3. A truss comprising a pad including a wall having a pair of vertical laterally spaced slots therein, a supporting bar for the pad having a portion slotted horizontally to coact with one of the slots in the pad and having another portion of the bar slotted angularly with respect to the other of the slots in the pad, and fastenings extending respectively through said slotted portions and slots and adjustable with respect to each for adjustably securing the pad to the bar.

4. A truss comprising a pad including a wall having a pair of vertical laterally spaced slots therein, a supporting bar for the pad having a portion slotted horizontally to coact with one of the slots in the pad and having another portion of the bar slotted angularly with respect to the other of the slots in the pad, and fastenings extending respectively through said slotted portions and slots and adjustable with respect to each for adjustably securing the pad to the bar, the slotted portions of the bar having longitudinally spaced slots, one of which is substantially straight lengthwise of the bar and the other of which is substantially in the form of an obtuse angle.

5. A truss comprising a pad including a wall having a pair of vertical laterally spaced slots therein, a supporting bar for the pad having a portion slotted horizontally to coact with one of the slots in the pad and having another portion of the bar slotted angularly with respect to the other of the slots in the pad, and fastenings extending respectively through said slotted portions and slots and adjustable with respect to each for adjustably securing the pad to the bar, the slotted portions of the bar having a single slot overlapping the pair of slots in the pad wall and with the portion of said single slot overlapping one of said pair of slots substantially straight lengthwise of the bar, and with the portion of said single slot overlapping the other of said pair of slots angularly offset from said straight portion at an obtuse angle.

JOHN GUTSCH.
